PRESSING DEVICE FOR BELT LOOP MATERIAL

Frank Greco, Hasbrouck Heights, N. J.

Application January 28, 1954, Serial No. 406,741

7 Claims. (Cl. 38—15)

This invention relates to a pressing device which has particular application to the problem of pressing belt loops after they have been prepared by the "blindstitch type" of sewing machine. While the device is particularly important in this application it is not limited thereto and can be used in other applications.

Belt loops for trousers are conventionally prepared by doubling a piece of fabric bringing the doubled portions together at about the center line. The loose ends are then sewn together by a "blindstitch" machine. This type of stitch causes the ends to be secured together but causes no visible stitch marks to show on the upper side of the belt loop. The conventional process thus produces a long strip of belt loop material which is then cut into convenient lengths and sewn in place upon a pair of trousers.

It has been found, however, that the strip of belt loop material, as it leaves the machine, is in unpressed condition and cannot be directly applied to the pair of trousers. It has therefore been common practice to press the belt loop strip as it is taken from the machine and then, after pressing, to cut it into convenient lengths.

The conventional sequence of steps, however, involves three separate operations which, in these times of high labor costs, are unsatisfactory.

The present invention permits a strip of belt loop material to be manufactured and pressed in one operation, and, where the novel cutter of this invention is also used, to also cut the strip of pressed belt loop material into the sizes required. The operation is completely automatic and can be performed with only semi-skilled labor.

Since the various fabrics of which belt loops are made have different temperatures at which they should be pressed the device is also provided with temperature controlling means as will be subsequently explained.

Briefly stated the invention comprises a feed member, a plate member provided with an opening therein adapted to emit steam, a heating device adjacent to the plate member, and a presser member in operating relationship with the plate member. The invention may also include a cutter member spaced from the plate member and in operating relationship with the feed member.

In the preferred modification of this invention the heating device is in abutting relationship with the plate member and temperature controlling means are provided in operating relationship with the heating device. A steam control valve is also provided in the preferred modification to control the emission of steam through the opening in the plate member.

It is preferable to drive the feed member by means of the sewing machine to which the pressing device is secured so that positive action may be obtained.

The invention will be further described by reference to the accompanying drawings which are made a part of this specification.

Fig. 1 is a side view of the pressing device attached to a "blindstitch" sewing machine with the cutting mechanism not shown.

Fig. 2 is a side view of the form of the invention shown in Fig. 1 without the cutting device.

Fig. 3 is a top view of the form of the invention shown in Fig. 2.

Fig. 4 is a sectional view showing the operation of the device taken along lines 4—4 of Fig. 2.

Fig. 5 is a sectional view taken along lines 5—5 of Fig. 4.

Fig. 6 is a sectional view showing the plate and presser members of the invention taken along lines 6—6 of Fig. 2.

Fig. 7 is a sectional view through the plate member showing the steam channels therein taken along lines 7—7 of Fig. 6.

Fig. 8 is a sectional view of the plate member and presser member showing the relationship thereof taken along lines 8—8 of Fig. 6.

Fig. 9 is a sectional view showing the means that may be used to move the presser member into and away from operating relationship with the plate member taken along lines 9—9 of Fig. 2.

Fig. 10 is a sectional view taken along lines 10—10 of Fig. 9.

Fig. 11 is a sectional view showing the operation of one type of feed member that may be used in this invention taken along lines 11—11 of Fig. 2.

Fig. 12 is a detail view of the bottom of the plate member of this invention showing the type of heating device that may be used.

Fig. 13 is a side detail view of the invention showing the means that may be used to operate the cutter member of this invention.

Fig. 14 is a side detail view of the form of the invention employing a cutter showing the relationship of the cutter to the other parts of the invention.

Fig. 15 is a detail view of the invention showing the timing device that may be used to actuate the cutter.

Sewing machine 11 is adapted to form belt loop 12 by the conventional blindstitch process. Belt loop 12 passes through opening 13 in shield member 14 which is secured to plate member 15. Plate member 15 is of appreciable thickness and is provided with intercommunicating steam channels 16, 17, 18, 19 and 20. Steam channel 20 is provided with openings 21 which communicate both with steam channel 20 and upper surface 22 of plate member 15. Plate member 15 is also preferably provided with cut-out portion 23 and openings 21 communicate with cut-out portion 23. Belt loop 12 is adapted to fit into cut-out portion 23.

Presser member 24 overlies plate member 15 and is adapted to produce pressing action upon belt loop 12. Presser member 24 is normally kept in operating relationship with plate 15 by means of springs 25 which are supported upon screws 26.

In order to prevent damage to the belt loop passing between plate member 15 and presser member 24 presser member 24 is formed with ears 27 at each end thereof.

Steam passes through steam channels 16—20 from a steam producing device of conventional type (not shown). The passage of the steam into channels 16—20 and thence through openings 21 is controlled by valve 28. Valve 28 is operated by the downward movements of arm 29 which is secured to arm 30 which in turn is secured to a foot treadle (not shown). Arm 31 bears spring 32 which causes arm 29 to return to its normal position when the pressure on the foot treadle is released. Adjusting screw 33 is provided to control the tension of spring 32.

Arm 29 is pivoted about support 34 and is held in place by screw 35. A drain valve 90 is located at the lowermost point of channels 16—20. Cock 91 controls the opening and closing thereof. Valve 90 is normally

closed but is opened whenever it is desired to drain the condensed water from channels 16-20.

Feed roller 36 is driven by shaft 37 which in turn is secured to bevel gear 38. Gear 38 is secured to bevel gear 40 which in turn is secured to shaft 39. Shaft 39 is secured to gear 41 which is driven by worm 42. Worm 42 is secured to shaft 43 which also bears pulley 44. Pulley 44, which is a drive roller, is driven by belt 45 which is driven by the sewing machine 11. Shaft 39 also bears gear 46 which drives the cutter of this invention as will be subsequently explained. Shaft 39, gear 41, worm 42, and shaft 43 constitute a speed reducing device.

Feed roller 47 abuts feed roller 36 and belt loop 12 passes between rollers 36 and 47. Roller 47 is secured to arm 48 which is pivotally movable upwardly about pivot 49a. Arm 48 bears link 49 which is secured within recess 50. Link 49 is also secured to link 51 which is secured to presser member 24.

Presser member 24 and feed roller 47 are moved out of operating relationship with plate 15 and feed roller 36 respectively by the upward movement of arm 48. Spring 52 is supported upon shaft 53 and its tension is controlled by adjusting screw 54. Operating handle 55 raises and lowers arm 48.

Support 56 is also provided to hold belt loop 12 in place and cause it to flow smoothly into a receptacle (not shown).

Plate member 15 is preferably formed with an additional cut-out portion 57 at the underside thereof. Heating device 58, which is preferably an electrical heating element, is disposed within cut-out portion 57. Heating element 58 is secured to a conventional thermostat 59 which is preferably of the compound bar adjustable type. Handle 60 varies the spacing of the contacts of the compound bar within thermostat 59 and thus controls the temperature that the heating device may assume. The heating element and thermostat are secured to a conventional power line (not shown).

The pressing device of this invention may also be equipped with a novel cutting device as shown in Figs. 13, 14 and 15. If this device is used the belt loops provided may be cut into the lengths desired in one operation. In this modification cutting table 61 is provided. Reciprocating cutting blade 62 abuts against cutting table 61 and cuts the belt loop as it moves downwardly. Cutting blade 62 is secured to shaft 63 which in turn is secured to arm 64. Arm 64 is in turn secured to arm 65 which is secured to operating member 66 of solenoid coil 67. Switch 68 actuates solenoid coil 67. Switch 68 is actuated by contact 69 which is moved into and out of engagement by cam roller 70. Cam roller 70 is driven by drive gear 46 which is driven by shaft 39 as previously explained. Drive gear 46 is changeable so that the speed of engagement of cam roller 70 with contact 69 can be controlled and thereby control the number of times that blade 62 moves downwardly. Since belt loop 12 is moving at a constant rate the size of the belt loop produced can be simply controlled.

While the operation of this device has been made clear by the foregoing description a graphic illustration of the operation of this device, including the cutter, will now be given.

Sewing machine 11 is operated and forms a continuous belt loop by the blindstitch method. As the loop 12 moves from the machine arm 48 is moved upwardly placing presser member 24 and feed roller 47 out of operating relationship with plate 15 and carrier roller 36. Prior to the operation of sewing machine 11 drive gear 46 which engages cam gear 70 and thus changes the period of reciprocation of cutter 62, has been selected of a size and number of teeth adapted to produce the size of belt loop desired. In addition thermostat 59 has been set to the fabric of which the belt loop is composed so that the correct heating temperature of plate 15 is produced.

With arm 48 in its upward position belt loop 12 is placed between rollers 36 and 47 and plate 15 and presser member 24. After this is done arm 48 is moved to its normal downward position so that belt loop 12 is moved by the action of carrier rollers 36 and 47 and is pressed by presser member 24 bearing against plate 15. Steam valve 28 is then actuated by the depression of arm 29. Steam then flows out of openings 21 and smooths out the irregularities in belt loop 12. Immediately, however, the heat of plate 15, which has been produced by heating element 58, dries the belt loop and removes the condensed water from the belt loop. The belt loop is also simultaneously pressed by being passed between presser member 24 and plate member 15.

As the pressed belt loop leaves plate member 15 and presser member 24, and after it passes between carrier rollers 36 and 47 it passes over table 61 and then comes in contact with cutter blade 62. Every time cutter blade 62 moves downwardly it cuts off a portion of belt loop 12. The reciprocating downwardly movement of blade 62 is controlled by gear 46 which meshes with gear 70 and thus controls actuator 69 which opens and closes switch 68 actuating solenoid coil 67 and causing operating member 66 to move reciprocatingly. When switch 68 is open return spring 80 causes shaft 66 to move to its open position. Thus, as shown, the machine carries out the intended purposes.

The foregoing specific embodiments of this invention as set forth in the foregoing specification and drawings are for illustrative purposes and for purposes of example only. Various changes and modifications can obviously be made within the spirit and scope of the invention and would occur to those skilled in this art. The scope of the invention is determined from the appended claims.

I claim:

1. A pressing device comprising a feed means, a plate member of appreciable thickness provided with a cutout portion in the upper surface thereof longitudinally of its length, said plate member being also formed with a steam channel therein, said plate member being also provided with a plurality of openings communicating with said steam channel and with said cut-out portion within said plate member so that steam may be emitted therethrough, said feed means being substantially aligned with the longitudinally extending cut-out portion; an electrical heating device adjacent said plate member, a presser member having a portion overlying said cut-out portion, and means adapted to move said presser member into and away from operating relationship with said plate member.

2. A pressing device for belt loop material comprising a feed means, adapted to transport material worked upon, a plate member of appreciable thickness forward of said feed means provided with a steam channel therein, said plate member being also provided with a plurality of openings communicating with said steam channel and the upper surface of said plate member so that steam may be emitted therethrough, valve means adapted to control the flow of steam into said steam channel; a heating device adjacent said plate member, a presser member above said plate member, means adapted to move said presser member into and away from operating relationship with said plate member, and a cutter member rearward of said feed means and in operating relationship with said presser member so that said material may be divided into proper sized portions immediately after being pressed.

3. A pressing device for belt loop material comprising a feed means, adapted to transport material worked upon, a plate member of appreciable thickness forward of said feed means provided with a steam channel therein, said plate member being also provided with a plurality of openings communicating with said steam channel and the upper surface of said plate member so that steam may be emitted therethrough, said plate member being

also provided with a cut-out portion upon the lower surface thereof; a heating device within said cut-out portion of said plate member, temperature controlling means in operating relationship with said heating device, valve means adapted to control the flow of steam into said steam channel of said plate member; a presser member above said plate member, means adapted to move said presser member into and away from operating relationship with said plate member, a cutter member rearward of said feed means in operating relationship with said presser member, and timing means controlling the period of reciprocation of said cutter member so that said material may be divided into proper sized portions immediately after being worked upon.

4. A pressing device for belt loop material comprising a pair of cooperating feed rollers adapted to transport said material, a plate member of appreciable thickness positioned forwardly of said feed rollers, said plate member being provided with a plurality of steam channels therein, a cut-out portion upon the lower surface thereof, and a plurality of openings communicating with one of said steam channels and the upper surface of said plate member so that steam may be emitted therethrough; a heating device within said cut-out portion of said plate member, temperature controlling means in operating relationship with said heating device, valve means adapted to control the flow of steam into said steam channels of said plate member; a presser member above said plate member means adapted to move said presser member into and away from operating relationship with said plate member said material being disposed between said plate member and said presser member; a cutter member rearward of said feed rollers and in operating relationship with said presser member, and timing means controlling the period of reciprocation of said cutter member so that said belt loop material may be divided into proper sized portions immediately after being pressed.

5. A pressing device comprising a pair of cooperating feed rollers, a plate member of appreciable thickness positioned forwardly of said feed rollers, said plate member being provided with a plurality of interconnected steam channels therein, a cut out portion upon the lower surface thereof, and a plurality of openings communicating with one of said steam channels and the upper surface of said plate member so that steam may be emitted therethrough; a heating device within said cut-out portion of said plate member, temperature controlling means in operating relationship with said heating device, valve means adapted to control the flow of steam into the steam channels of said plate member, additional valve means adapted to permit condensed water to be removed from said steam channels; a shield member at the forward portion of said plate member, a presser member, and means adapted to move said presser member into and away from operating relationship with said plate member.

6. A pressing device comprising a pair of cooperating feed rollers, a plate member of appreciable thickness positioned forwardly of said feed rollers, said plate member being provided with a plurality of interconnected steam channels therein, a cut-out portion upon the lower

surface thereof, and a plurality of openings communicating with one of said steam channels and the upper surface of said plate member so that steam may be emitted therethrough; a heating device within said cut-out portion of said plate member, temperature controlling means in operating relationship with said heating device, a steam control valve member controlling the flow of steam into said steam channels, a drain valve adapted to remove condensed water from said steam channels, a presser member, an arm member secured to said presser member and to one of said feed rollers adapted to be moved upwardly so that said presser member may be moved into and away from operating relationship with said plate member, and a shield member at the forward portion of said plate member.

7. A pressing device comprising a drive roller, a shaft secured to said drive roller, a speed reducing device secured to the other end of said shaft, a pair of cooperating feed rollers, one of said feed rollers being actuated by said speed reducing device, a plate member of appreciable thickness positioned forwardly of said feed rollers, said plate member being provided with a plurality of interconnected steam channels therein, a cut-out portion upon the upper surface thereof, a cut-out portion upon the lower surface thereof, and a plurality of openings communicating with one of said steam channels and said cut-out portion upon the upper surface of said plate member so that steam may be emitted therethrough; a heating device within said cut-out portion upon the lower surface of said plate member, temperature controlling means in operating relationship with said heating device, a steam control valve member controlling the flow of steam into said steam channels, a drain valve adapted to remove condensed water from said steam channels, a shield member at the forward portion of said plate member, a presser member, an arm member secured to one of said feed rollers and to said presser member adapted to be moved upwardly so that said feed rollers may be moved into and away from operating relationship with each other and said presser member may be moved into and away from operating relationship with said plate member, spring means normally keeping said presser member in operating relationship with said plate member, and additional spring means normally keeping said arm member in downward position.
